ELECTRICAL APPARATUS

Herbert C. Walters, Dayton, Ohio, assignor to
Delco Aviation Corporation, Dayton, Ohio, a
corporation of Delaware

Application March 30, 1931, Serial No. 526,474

1 Claim. (Cl. 177—311)

This invention relates to ignition mechanism and more particularly to a combined apparatus for delivering ignition energy to an internal combustion engine and for indicating the timing of such energy.

It is highly desirable in various instances to employ in combination with an internal combustion engine ignition system, some mechanism whereby the timing of the ignition may be readily and easily observed in order that the engine ignition may be quickly and correctly adjusted to result in the most efficient operation. It has also been found desirable to utilize mechanism such as that referred to above, in connection with investigations of the characteristics of fuels used in internal combustion engines, as for example, the determination of the anti-knock qualities of particular fuels.

It is accordingly one of the objects of the present invention to provide novel mechanism whereby the timing of the ignition of an internal combustion engine may be readily and accurately observed.

Another object of the invention is to provide a novel mechanism of the above character embodying a circuit breaker mechanism which also serves as the timer structure for the ignition circuit.

Still another object is to provide a novel combined circuit breaker and spark protractor whereby there is embodied in a single unitary structure, the ignition energy circuit making and breaking mechanism together with the novel apparatus for indicating the timing of the ignition spark.

A further object is to provide in a device of the above character, a novel arrangement of parts whereby a simple and compact structure is obtained, and one which is readily adaptable to internal combustion engines wherein its use will result in extreme ease in the determination of the exact timing of the ignition spark and the subsequent adjustment for most efficient operation.

The above and other objects will appear more fully hereinafter from the following detailed description when taken in connection with the accompanying drawing wherein one embodiment of the present invention is illustrated. It is to be expressly understood, however, that the drawing is for purposes of illustration only and is not to be taken as a definition of the limits of the invention, reference being had for this purpose to the appended claim.

In the drawing:—
Fig. 1 is a front view of a combined circuit

breaker and spark protractor embodying the principles of the present invention;

Fig. 2 is a vertical section of the apparatus illustrated in Fig. 1;

Fig. 3 is a vertical section taken substantially on line 3—3 of Fig. 2; and

Fig. 4 is an ignition circuit wiring diagram embodying the invention.

Referring more particularly to Figs. 2 and 3 of the drawing, a structure embodying the present invention is illustrated therein as embodying a housing having an intermediate portion 5 adapted to house circuit making and breaking mechanism 6, a forward enlarged portion 1 adapted to house the spark indicating means 8, and a reduced rear portion 9 forming a bearing for the timing shaft 10 of an internal combustion engine, the said shaft being adapted to actuate the mechanism 6 and the spark indicating means 8, as will be more particularly referred to hereinafter.

Means are provided for supporting the circuit breaker mechanism 6 within the housing portion 5, and preferably such means are so constituted as to be adjustable in order that the timing of the interruption of the ignition circuit controlled by the mechanism 6 may be readily varied. In the form shown, such supporting means are constituted by a base plate 11 to which is secured a bracket 12 adapted to support relatively movable contacts 13 and 14 as by means of arms 15 and 16 respectively. Relative movement between the contacts is effected by operation of a resilient actuating arm 17 carrying a cam follower or rubbing block 18 at its outer end cooperating with the outer end of the arm 15 and with the surface of a cam 19 carried by shaft 10. In order to vary the position of the circuit breaker 6 relative to the cam 19, and thus adjust the ignition timing, an adjusting member 20 is provided, the said member having screw-threaded engagement with a flange 21 of the plate 11, and being movable angularly, in a slot 22 provided in the housing portion 5, with the plate 11 to adjust the position of same. After such adjustment has been effected, the member 20 may be tightened in order to secure the parts in their adjusted position.

In order to provide the necessary electrical connections for the relatively movable contacts 13 and 14, the arms 15 and 16 are connected to the opposite terminals of a condenser 23 by means of leads 24 and 25 respectively. The terminal of the condenser connected to the arm 15 is thereafter connected to a terminal 26 by a flexible connection 27 while the other terminal of the condenser is connected to a terminal 28 by

by flexible connection 29. Each of the terminals 26 and 28 is suitably insulated from the housing portion 7.

Means are carried by the forward portion of 5 the shaft 10 for indicating the timed relation between the engine shaft and the occurrence of the ignition spark and preferably such means are housed within the casing portion 7. As shown such means are constituted by an arm 29 of insulating material, secured to the forward end 10 of the cam 19 as by means of a pin 30 and screw 31. The pin 30 is adapted to cooperate with either of the openings 32 or 33 in order to adapt the apparatus for efficient operation in either a 15 clockwise or counter-clockwise direction, the arcuate distance between the openings 32 and 33 representing substantially the degree of backlash in the driving gears. The outer portion of the arm 29 is adapted to removably support a 20 glow discharge tube 34, which may be of the type filled with neon gas, the support for this tube comprising spring brackets 35 and 36. The former of these arms is spaced a short distance from the housing portion 7, which is connected 25 to ground, while the other arm 26 is electrically connected to a terminal stud 37, such connection being effected by a resilient arm 38 adapted to bear upon the inner rounded end of the stud 37.

30 The outer open end of the housing portion 7 is preferably closed by an insulating plate 39 secured to the housing by means of screws 40 and carrying at its center the stud 37. Adjacent its outer portion, the plate 39 is provided with an 35 arcuate slotted opening 41 permitting the observation of the tube 34 through a narrow slit 42 provided in a member 43 secured to the arm 29, the said slit also registering with a second slit 44 in the arm 29 located adjacent the tube 40 34. By this construction, a substantially narrow pencil of light emitted by the tube 34 when the same is energized, as will appear hereinafter, may be observed through the opening 41. A stationary scale or protractor 45 which is preferably 45 graduated in a manner to correspond with the position of the engine flywheel, is secured to the cover plate 39 directly above the opening 41 and cooperates with the spark indicating means 8 to indicate the number of degrees of retardation or 50 advancement of the flywheel when sparking energy occurs.

In order to properly electrically connect the above-described structure in an ignition system, the terminal 28 is connected to one end of a suitable ignition coil primary winding 46 through a lead 47, while the other terminal 26 of the circuit breaker is connected to one side of a battery 48 by means of a lead 49. The primary circuit is completed by a lead 50 in which a suitable switch 55 55 51 may be inserted. A secondary coil 52 is connected at one end, to ground indicated at G by a connection 53, and the other end of the secondary is electrically connected as by means of a lead 54 to a spark plug 55 adapted to furnish 60 the sparking ignition energy for the internal combustion engine. The spark indicating device 8 is connected in parallel with the spark plug 55 and such connection is preferably effected by a lead 56 which is adapted to be secured to the 65 70 terminal stud 37.

From the above it will readily be observed that in operation, with the shaft 10 drivably connected to any suitable rotatable portion of the engine, rotation of said shaft will not only effect 75 operation of the circuit breaker 6 in order to sup-

ply ignition energy to the engine, but such rotation will also effect movement of the indicating mechanism 8 in timed relation with the engine, and the glow discharge tube 34 embodied in such mechanism will be energized during each periodic 5 actuation of the contacts 13 and 14. Upon each actuation of the circuit breaker, ignition energy will be conducted to the spark plug through the connection 54 with the secondary coil 52, as well understood in the art, in order to ignite the explosive charge which has been drawn into the cylinder of the engine. Some of this energy will pass through the tube 34 by means of connection 56, stud 37, resilient arm 38 and spring bracket 36, the energy passing to the grounded housing 15 portion 7 from the bracket 35 after passage through the tube, the space between said last-named bracket and the housing functioning as a small condenser, indicated at 57 in dotted lines in Fig. 4.

20 During each successive energization of the spark plug 55 and the glow tube 34, the light emitted by the latter may be observed through the opening 41 and aligned slits 42 and 44. The position which this pencil of light occupies, during rotation of the arm 29 and tube 34, relative to the scale 45 will serve as an accurate indication of the exact time at which the spark occurs in the engine cylinder relative to the position of the engine piston or flywheel. If it is desired to either advance or retard the timing of the spark, it is only necessary to loosen the adjusting member 20 and move the same together with the base plate 11 and circuit breaker mechanism mounted thereon, in the desired direction. 25 Such adjustment, as well understood, will serve to vary the position of the contacts 13 and 14 relative to the cam 19.

30 There is thus provided by the present invention a novel combined ignition circuit breaker 40 and spark protractor for producing the ignition energy for an internal combustion engine as well as indicating the precise timing relation between the occurrence of the sparking energy and the position of the engine flywheel. This unitary 45 construction embodies readily adjustable means for varying the timing of the ignition spark, which renders the device especially adaptable for use in determining the characteristics of internal combustion engine fuels, as for example, the 50 anti-knock quality thereof, inasmuch as the operator may readily vary the timing and simultaneously therewith visually observe the exact 55 degree of variation by the cooperation between the glow discharge tube and the stationary protractor.

60 While there has been shown and described only one embodiment of the present invention, it is to be understood that the same is not limited thereto but may be embodied in various electro-mechanical forms. For example, while the mechanism has been shown for use in connection with an internal combustion engine having a single cylinder, it will be apparent that the same may be readily adapted for use in connection with 65 engines having a plurality of cylinders, it being merely necessary to provide additional lobes to the cam for actuating the circuit breaker mechanism and to include the usual high tension distributor. In such event the high tension lead 70 from the secondary of the ignition coil may also be connected to the spark indicating mechanism and the protractor and slotted opening in the housing extended to include 360° in order that the timing of every spark may be observed. It 75

will also be understood that the spark indicating mechanism may be used alone, if desired, and a separate circuit making and breaking mechanism may be employed. Various other changes 5 may be made in the relative sizes and shapes and location of the component parts of the invention, as well understood by those skilled in the art, without departing from the spirit thereof. Reference will therefore be had to the appended 10 claim for a definition of the limits of the invention.

What is claimed is:

A combined circuit breaker and spark 15 tractor for the ignition circuit of an internal combustion engine comprising a housing, a circuit breaker mechanism within said housing for periodically interrupting said ignition circuit to produce electrical impulses therein, a rotatable

cam shaft extending into said housing to periodically actuate said mechanism, said shaft being rotatable in timed relation with the timing shaft of the engine, means extending through a slot in the housing and accessible from the exterior 5 of said housing for adjusting the position of said mechanism with respect to said shaft, an arm within said housing carried by said shaft, a glow discharge tube secured to said arm, a cover plate for said housing, said plate having an 10 opening registering with said tube in one position of its rotatable movement, said opening being elongated in the direction of movement of said tube, scale means carried by said plate adjacent said opening and cooperating with said tube, 15 and means for electrically connecting said tube in parallel with the ignition circuit.
